(57) **CLAIM**

The ornamental design for a flexible glove with a honeycomb pattern and a flared cuff, as shown and described.

DESCRIPTION

FIG. 1 is a front elevation view of the flexible glove with a honeycomb pattern and a flared cuff in accordance with our design, wherein the glove is illustrated for a left hand; and wherein a front elevation view of a glove for a right hand is a mirror image thereof;

FIG. 2 is a rear elevation view of the glove of FIG. 1, wherein a rear elevation view of the glove for the right hand is a mirror image thereof;

FIG. 3 is a left side elevation view of the glove of FIG. 1, wherein a left side elevation view of the glove for the right hand is a mirror image thereof;

FIG. 4 is a right side elevation view of the glove of FIG. 1, wherein a right side elevation view of the glove for the right hand is a mirror image thereof;

FIG. 5 is a top plan view of the glove of FIG. 1, wherein a top plan view of the glove for the right hand is a mirror image thereof;

FIG. 6 is an enlarged detail view of the area circumscribed within FIG. 1, showing the honeycomb pattern that is provided on the gripping surfaces of the glove; and, FIG. 7 is an enlarged cross-section of the pattern shown in FIG. 6;

The broken lines in the drawings show portions of the glove or environment and form no part of the claimed design.

The dot-dot-dash line surrounding the detail area in FIG. 1 and corresponding view in FIG. 6 depicts the boundary of the detail and forms no part of the claimed design.
